UNITED STATES PATENT OFFICE.

ALEXANDER FROMHOLD, OF RUTHERFORD, NEW JERSEY, ASSIGNOR TO FRANK VOIGTMANN AND S. HARRIS POMEROY, DOING BUSINESS UNDER NAME OF VOIGTMANN & COMPANY, OF NEW YORK, N. Y.

WINDOW-FRAME.

1,048,062.

Specification of Letters Patent. Patented Dec. 24, 1912.

Application filed January 4, 1909. Serial No. 470,666.

To all whom it may concern:

Be it known that I, ALEXANDER FROMHOLD, a citizen of the United States, residing at Rutherford, in the county of Bergen 5 and State of New Jersey, have invented certain new and useful Improvements in Window-Frames, of which the following is a specification.

This invention relates to the art of sheet 10 metal window frames, and pertains more especially to that class of sheet metal frames employing hollow side frame members or stiles made from suitably bent sheet metal.

The main object of the invention is to 15 provide a construction that shall be strong and durable and adapted for use especially as a fire proof window frame to firmly hold the glass pane in position against the action of water forced against the window pane.

20 Another object of the invention is to provide a metal sash the body of which will not be liable to distortion or twisting under the action of heat.

A still further object of the invention is to 25 provide an improved means for facilitating the insertion of the pane and for securely binding the latter and the frame together.

Other minor objects and advantages will appear in connection with the following description of the preferred embodiment of 30 the invention as represented in the accompanying drawings, in which latter—

Figure 1 is a perspective view of a section of my improved window frame; and Fig. 2 35 is an enlarged cross section through one of the side frames thereof.

Referring to the drawings, 3 represents as 40 an entirety the side sections of the sash frame, that are preferably formed from a single piece of sheet metal so bent as to provide an outer bearing surface 4 adapted to engage the window casing and having an anchoring portion 5 for engagement with a bead or rib on the window casing to hold 45 the latter and said side frames together.

The bearing surface 4 is preferably formed with an integral over-lapped section 6 which permits a slight transverse stretching of the bearing surface under the action 50 of heat or other strains without destroying the sash. From the bearing surface 4 the sides 7 of the sash are extended, being bent approximately at right angles to the bearing surface, and at their inner portions be-

ing bent toward each other as shown at 8 55 and 8^a, and thence inwardly forming flat glass engaging strips 9. These strips 9 are preferably convergent toward their free edges, so as to provide spring binding members adapted to engage and clamp the glass. 60

In order to strengthen and make more rigid the side sections I provide an integral internal reinforcing member 10 adapted to bear against the inner surfaces of the base 4, sides 7 and inclined portions 8 and 8^a, the 65 free edges of said reinforcing member abutting against the bases of the glass engaging strips 9. This strengthening member 10 preferably consists of a stiff channel shaped piece of steel or other elastic material. In 70 the preferred construction the portion 8^a of one of the sides of the sash frame is slightly curved transversely, as best shown in Fig. 2, the reinforcing strip bearing against the concaved portion of said side 75 member 8.

The hollow intermediate cross bar 11 is secured to and between the side frame members and is provided with a groove 12 in which one edge of the glass pane 13 is 80 adapted to be seated. The preferred manner of securing the cross bar to the side frame members is by soldering one side of said cross bar thereto and leaving a free engagement at the opposite side, whereby 85 one side of the cross bar and the sides of the side frame members engaged thereby may be drawn tightly together by means of the screws 14 connecting the two sides of the cross bar. 90

In the construction herein shown the side frame members and cross bar represent a portion of a window sash adapted to hold two window panes, one above and one below the cross bar, with the side frame members extended and connected at their ends by end cross bars formed similar to the intermediate cross bar 11, but as such a form or organization of sash frame is well known in the art it is not necessary to show it in 100 its entirety. It is, however, to be noted that the upper edge 15 of one side of the cross bar is slightly lower than the corresponding edge 16 of the other side, whereby, when the metallic frame is assembled, the glass may 105 be inserted within the groove 12 without requiring the adjustment of one of said cross bars, it being necessary only to loosen

the main screws 17 which connect the opposite sides of each side frame sufficiently to spread the strips 9 for the introduction of the glass, whereupon the latter may be readily inserted between the side frames and cross bars, and then by tightening the screws 17 the strips 9 will be tightly drawn against the glass for the purpose hereinbefore mentioned. The method, however, of 10 securing the glass before or after the sash is assembled is immaterial and constitutes no part of this invention.

Without confining myself to the exact details of structure herein shown and described, I claim:

15 A metal window sash having a hollow side frame member formed integral of sheet

metal and having inwardly projecting flat glass engaging strips converging toward each other and springing to clamp the edge 20 of a window pane between their bases, the inner ends of said strips being entirely free, and a reinforcing lining of sheet metal for the hollow side frame having intimate contact with the walls of said side frame and 25 having its ends abutting edgewise against the strips at the bases thereof and adjacent the edge of the window pane to be supported to thereby prevent spreading of the strips at the base thereof.

ALEXANDER FROMHOLD.
